INSULATION

Walter T. Peirce, Worcester, Mass., assignor to
The American Steel and Wire Company of New
Jersey, a corporation of New Jersey

Application October 7, 1932, Serial No. 636,726

2 Claims. (Cl. 173—264)

This invention relates to electrical insulation constructions and particularly to those characterized by laminated dielectrics arranged with more or less adjacent edge portions. One object 5 is to improve the breakdown characteristics of such constructions.

In the accompanying drawing—

Figure 1 is a longitudinal cross-section of a commonly used cable insulated by a laminated dielectric.

Figure 2 is a longitudinal cross-section of a specific form of the present invention.

Figure 3 is a modification of Figure 2, and

Figures 4 and 5 illustrate enlarged sections of the dielectrics shown in the first and second figures respectively.

Figure 1 shows an electric conductor 1 insulated by spirally wound paper strip layers 2 which are impregnated with oil and covered by a lead sheath 3. The impregnating oil is supposed to completely fill all interstices between the paper strip. Actually, however, unimpregnated areas sometimes exist between adjacent edges of the tape convolutions.

In the drawing, which is illustratively exaggerated, a line A—A is drawn through such an unimpregnated area. This means that there is an air space between the tape convolutions whose edges are adjacent this line. A second line B—B is drawn through a tape convolution whose edge is adjacent this air space. Both of these lines indicate stress paths from the conductor 1 to the lead sheath 3 which is assumed to be grounded. In case the sheath 3 were non-conducting they would indicate paths to an external grounded object.

The line A—A passes through paper, air and oil while the line B—B passes only through paper and oil. This means that there will be a potential difference between the two lines which will set up tangential stresses therebetween. That is to say, the potential differences between the extremes of the air gap cut by the line A—A greatly exceed those on the sides of the strip cut by the line B—B because of their respectively different dielectric constants. In the case of relatively large voltages this ratio may increase rapidly as the result of the air's ionization. Once an arc is begun the cable rapidly deteriorates throughout a constantly enlarging area.

It will be seen that cable breakdowns of the character under discussion seem to be directly the result of more or less minute air spaces. However, even in the absence of such voids a breakdown may result. This follows from the fact

that even though all interstices are completely impregnated the different dielectric constants of oil and paper may result in relatively large potential differences occurring at points which introduce stresses parallel to the wound insulation's surfaces. 5

Figure 2 illustrates a construction which diminishes the foregoing trouble to a great degree. This construction shows the same conductor 1 insulated by oil impregnated paper tape 2^a, over 10 which is applied the lead sheath 3. It will be observed that here the paper tape tapers to a point at each of its edges. Such tape may be manufactured by calendering its edges. It is applied so that the enlarged tape bodies of each successive layer overlie the reduced edge portions of the one beneath, whereby the interstices or voids are reduced to such a minimum that the probability of the described breakdown will be almost inconsequential. Also, the tangential stresses 15 remaining will be spread over the whole width of the tape rather than concentrated at the edges. 20

A still further feature lies in the fact that it is possible to apply the tape with lapped convolutions and thereby secure a greater baffling action 25 without seriously impairing the cable's flexible characteristic. Such a construction is illustrated by Figure 3. This last figure shows the lead sheath 3 eliminated and a fabric covering 3^a substituted. 30

As shown particularly well by Figure 5, the tape 2^a tapers from its central portion to its pointed or sharpened edges symmetrically respecting its center line so that these edges are at the latter, and its surfaces are smoothly and evenly curved. This tape is wound over the conductor 1 in layer form with the respective edges of its laterally adjacent convolutions in mutually opposed alignment, as shown by Figures 2 and 3. 40 The oil impregnation fills the interstices between the tape as much as is possible. 45

It will be seen that the invention primarily embodies the use of dielectrics which have edge portions of less cross-sectional area than their central portion, and is especially applicable to cases where the dielectrics have different specific inductance capacities. Preferably the edges are rather sharp although a somewhat more oval shape will accomplish the same results to a lesser degree. In the example shown the tape may be of any insulating material, and the cable as a whole may be constructed in other forms than those specifically shown. 50

I claim:

1. A high voltage electrical conductor and insulation therefor, said insulation including dielectric tape having sharpened edges and which tapers from its central portion to its sharpened edges symmetrically respecting its center line so that said edges are at the latter, said tape being wound over said conductor in layer form with the respective edges of its laterally adjacent convolutions in mutually opposed alinement and having its interstices filled with a fluid dielectric as much as is possible, said tape having smoothly curved surfaces.
